(57) **CLAIM**

The ornamental design for a leg protection device, as shown and described.

DESCRIPTION

FIG. 1 is perspective view of a leg protection device showing my new design in an assembled condition; FIG. 2 is a top orthogonal view thereof; FIG. 3 is a front orthogonal view thereof; FIG. 4 is a side orthogonal view thereof as taken from the left side of FIG. 3; FIG. 5 is a side orthogonal view thereof as taken from the right side of FIG. 3; FIG. 6 is a rear orthogonal view thereof; FIG. 7 is a bottom orthogonal view thereof; and, FIG. 8 is a perspective view thereof shown in a disassembled condition for clarity of illustration.
